GARMENT CONSTRUCTION

Isadore B. Kay, Chicago, Ill.

Application January 21, 1937, Serial No. 121,525

2 Claims. (Cl. 2-93)

The present invention relates to a garment construction and method of making the same and more particularly to expandable pockets provided therein.

5 Heretofore, in the manufacture of coats, it has been proposed to provide a patch pocket, which was sewed over the material, and unless due care was exercised in positioning the same, the surface design of the material had to be carefully 10 matched, and when in use, the pocket would become bulgy and wrinkled.

It is an object of the present invention to provide an expandible pocket which may be built in a garment, and which gives to the garment a 15 neat, finished appearance, and wherein the pleats will permit the pocket to expand without distorting or causing wrinkling of the garment when an article is placed in the pocket.

A further object is to provide a coat blank 20 with a cut-out portion between the front and rear panels and to pleat the portion of material below the cut-out portion, so as to, in effect, have somewhat the appearance of the average coat while permitting the pleats to be easily 25 opened without distorting the front panel of the coat when an article is placed in the pocket, and whereby the pleats will readily reposition themselves to their normal positions when the article is removed.

30 Referring to the drawing:

Figure 1 illustrates a side view of a completed coat having a pocket embodying the present invention.

Figure 2 is an enlarged partial detail view, illustrating the completed pocket in elevation.

Figure 3 is an enlarged cross-sectional view taken on the line 3—3 of Figure 2.

Figure 4 is an enlarged partial detail view showing the inner side of the pocket shown in 40 Figure 2.

Figure 5 is a view of the front of the coat blank.

Figure 6 is a modified form of the front of the coat blank wherein the portion forming the 45 pocket is of a separate piece.

Figure 7 illustrates a diagrammatic view of the portion attached to Figure 6 to form the pocket; and

Figure 8 is an enlarged cross-sectional view 50 of the pocket and portion attached thereto, shown in Figures 6 and 7.

The invention relates more particularly to the front panel of a coat which is designated by the numeral 10. The general contour of the blank 55 will vary in accordance with the style of coat to

be made, but the general principles herein disclosed will be substantially the same with all of the styles. The front panels are sewed to a rear panel 11 which may be of any suitable construction in accordance with the style of back employed in the construction of the coat, without departing from the principles employed in constructing the pockets.

The front panel 10 is provided with an arm-hole or recess 12 which has a cut-out portion 13 10 that may be of any suitable shape, and which forms an upstanding portion 10a that is brought to engage the portion 10 so as to provide a form-fitting coat or the straight or box type of coat. The cut-out portion 13 extends downwardly and 15 is preferably cut horizontally at 14 so as to form the top edge of the pocket of the coat, and this horizontal cut extends partially through the forward portion of the panel and has a small cut-out portion 15 extending upwardly therefrom 20 which provides for a seam to assist in fitting the coat to conform to the body of the wearer.

When the pattern is thus cut, (Fig. 5), the material between the horizontal cut 14 and the bottom edge of the pattern is pleated along dot 25 and dash lines 16 to form folds, as shown in Figure 3. These folds 16 may be parallel vertical pleats or of any other suitable style, such as diagonal or of the converging type. When pleated, the cut-out portion 13 is then brought into juxtaposition, so as to provide for a seam 17 extending from the arm opening or recess 12 to the horizontal cut 14 which forms the top edge of the pocket. The top edge of the pocket is then finished off to form a piped pocket opening, as 30 shown in Figure 2, or it may be finished to form a welt or flap type of pocket. Then the lower edge of the front panel 10 is turned to form a finished edge 18 of the coat, and this turning provides for securing the lower edge of the folds or pleats 16 in position, as indicated in Figure 2. After 35 the front panel has been constructed as above described, a pocket 19 of any suitable material is then secured in position with the opening thereof aligned with the edge of the horizontal cut 14 and the usual lining (not shown) may then be applied.

As shown in Figure 1, the hand or an article may be placed in the pocket 19 which will cause the same to bulge and the pleats 16 will then 50 expand between their top and bottom edges 14 and 18 without exerting a pull to the front or back portions of the panel.

While the coat is buttoned and an article is placed in the pocket, these pleats 16 will expand 55

freely and the extreme front edge of the front panel 10 will not be caused to flare outwardly or pull, as the amount of yield provided in the pleats will suffice for articles placed within the pocket.

5 In Figure 6, I have shown a modified form of front panel 10b, which is preferably constructed with an arm-hole or recess 12a and is cut to extend downwardly along the line 13a to a horizontal cut 14a that forms the opening for the 10 pocket in the same manner as shown in the preferred form, (Fig. 5). The portion between the 15 pocket opening and the lower edge of the coat has an insert 20 that is sewed to the front panel 10a at 21, and which insert is provided with a plurality 20 of substantially vertical pleats 16a that extend toward the back of the coat and are secured to a portion 10c of the panel 10b by a seam 22. When the insert 20 is pleated, the portion 10c is brought in juxtaposition to form a seam along the line 13a 25 in the same manner as that shown in Figure 5.

In this modified form the appearance of the coat when completed is the same as that shown in Figure 1, the difference being that an insert is provided to form the space provided by the cut-out portion 13 in Figure 5, and, when completed, the 25 seams 21 and 22 will not be visible, as shown in Figure 8.

While I have shown my improved type of pocket as built into a suit coat, the same may be employed in the construction of a vest, an overcoat,

or the like. When built into an overcoat, the lower edge of the pleats may be left free so as to permit of their opening while the person is walking, and the top portion of the pleats will serve in the same manner as above described, when the person has his hands or an article in the pockets.

5 I claim:

1. A coat blank having integral front and back forming members, the blank having a horizontal pocket forming slit intermediate its upper and lower edges, the front and back forming members being spaced apart above said slit by a cut out portion which extends upwardly and merges into spaced apart armhole forming portions, the front and back forming members being continuous 15 below said pocket forming slit.

2. A coat having integral front and back forming members, armholes and horizontal side pocket openings, a side seam joining said front and back forming members and extending from an armhole 20 downwardly and terminating at the pocket opening, the coat material below said slit being continuous and having vertical pleats extending to the lower edge of the coat and secured at their top and bottom ends by stitching, said pleated region 25 forming one side of an expansible pocket, and being integral with the front and back sections above said pocket opening.
